UNITED STATES PATENT OFFICE.

GEORGE L. PIERCE, OF BROOKLYN, NEW YORK.

GOLF-BAG.

1,095,670.

Specification of Letters Patent. Patented May 5, 1914.

Application filed April 1, 1912. Serial No. 687,555.

To all whom it may concern:

Be it known that I, GEORGE L. PIERCE, a citizen of the United States, residing at Brooklyn, in the county of Kings and State 5 of New York, have invented certain new and useful Improvements in Golf-Bags, of which the following is a specification.

My present invention is an improvement in the construction of golf-bags relating 10 more particularly to the bottom of the bag.

Depending upon the particular embodiment of the invention, it has some or all of the following features and advantages:—It keeps the bottom of the bag off the ground 15 so that the sagging of the bottom under the weight of the clubs does not show, nor does it interfere with the standing of the bag squarely on its bottom; it keeps the bottom stitching out of contact with the ground 20 so that in dragging or trailing the bag said stitching is not worn through. These and other features and advantages of my invention will be understood by those skilled in the art from an understanding of the following description in connection with the 25 drawings.

In these, Figure 1 is a side elevation of a golf-bag within my invention; Fig. 2 is a vertical section on an enlarged scale of the 30 lower end of the bag of Fig. 1; Fig. 3 shows the longitudinal seam-side of the bag to illustrate a form of seam-protector; and Fig. 4 shows a modified form of seam-protector.

35 I will now describe the specific devices of the drawings with the preface that the expressions "downwardly" and "upwardly", etc., as used in the specification and claims, refer to the bag when held in the upright 40 or inclined positions shown in the drawings.

1 is a golf-bag whose side portion 2 comprises a canvas upper part 2^a and a leather lower part 2^b. Of course, the bag might be 45 made of other materials, for example, might be made all of leather.

3 is the bottom piece of the bag having a downwardly extending peripheral flange 3^a. The lower side portion 2^b of the bag 50 extends below the bottom 3 and thence folded back on itself adjacent the flange 3^a and said side portion and flange are there secured together by circumferential stitching 4.

5 is stuffing material within the fold of 55 the side portion 2^b, best described as being a ring around the lower edge of the bag, and may consist of metal, ratan, etc.

Of course, the longitudinal edges of the side portion of the bag must be secured together by a seam 6 and this longitudinal seam, for better appearance and finish of the bag, is usually put on its under side,—that is to say, on the side which is opposite the handle 7. The result is that the 65 lower portion of this seam contacts with the ground and wears through when the bag is trailed or dragged. To protect this portion of the seam, I show two forms of guard for straddling the lower edge of the bag 70 over the seam. In Fig. 3, 8 is a piece of leather folded back on itself over the seam 6 and is permanently secured in said protective position by rivets 9. On the other hand, Fig. 4 shows a U-shaped metal clip 75 10 adapted to be sprung into straddling position on the lower edge of the bag immediately over the seam 6 which is then fully protected from abrasion. Figs. 1 and 2 show this clip in use.

When the ring 5 is made of iron and is fairly heavy, it gives a good balance to the bag and makes it tend to stand up by lowering its center of gravity.

My bag construction permits the circumferential stitches 4 to be located so high up as not to touch the ground either when the bag is resting squarely on its bottom or when it is trailed. Any sagging of the bottom 3 due to the weight of the clubs does not 90 show from the outside. Further, the bag does not become round-bottomed to interfere with its standing squarely upon its bottom.

What I claim is:

1. A golf bag comprising a lower tubular side wall of relatively rigid material, a bottom located within the said wall above the lower edge of the same and secured to said side wall, and a substantially rigid ring located within and inclosed by the portion of the side wall that projects below the bottom, said projecting portion and ring forming a support for maintaining the bottom above the surface on which the bag is placed.

2. A golf bag comprising a lower tubular side wall of relatively rigid material, a relatively rigid bottom located within the said

wall above the lower edge of the same and having a downturned flange secured to said side wall within the same and terminating short of its lower edge, and a substantially rigid ring located within the said side wall below the said flange, the lower margin of the said side wall being folded inwardly around the ring and secured thereto, form-

ing a support for maintaining the bottom above the sun face on which the bag is placed. 10
In testimony whereof I affix my signature in presence of two witnesses.

GEORGE L. PIERCE.
